F. V. Winter

Attorney

UNITED STATES PATENT OFFICE.

AARON BERKOWITZ, OF NEWARK, NEW JERSEY.

ATTACHMENT FOR PARASOL AND UMBRELLA HANDLES.

Application filed May 29, 1926. Serial No. 112,578.

This invention relates to improvements in attachments for parasols and umbrellas or the like, and specifically has to do with improvements embodying means for securing 5 said parasol or umbrella in closed position.

The principal object of the invention resides in the production of a device adapted to be secured to the supporting stem or shank portion of an umbrella or a parasol 10 whereby the same may be conveniently supported from the wrist.

Another object of the invention is to provide means for securing the tips of the ribs of the umbrella or parasol within the device 15 and thus maintain the cover portion in folded position.

Still another object resides in the provision of reciprocating means adapted to cooperate with certain other parts to affect 20 the object aforesaid.

A further object of this invention is to provide a device of the above described character that can be applied to all forms 25 of umbrella or parasols without changing or injuring the same.

Other objects or advantages will be apparent as the nature of the invention is better set forth, and it will be understood that changes within the scope of the claims may 30 be resorted to without departing from the spirit of the invention.

In order that the invention may be better understood, reference is had to the accompanying drawings, forming a part of this 35 specification and in which:

Figure 1 is a side elevation of the device applied to the handle of an umbrella or parasol.

Fig. 2 is a central longitudinal sectional 40 view thereof, certain movable parts being in the position they would assume were the umbrella or parasol in open position.

Fig. 3 is a view like unto Fig. 2, but here 45 certain movable parts are shown retarded and exerting sufficient pressure upon the ribs of the umbrella or parasol to hold the same in closed position; and

Fig. 4 is a central longitudinal sectional 50 view of a slightly modified form of handle embodying the spirit of the invention.

The present day umbrellas, so far as I am aware, are not provided with means for retaining the ribs of an umbrella or parasol

in close relation to the handle portion of the same, aside from the well-known strap which encircles the lower portion of the umbrella cover for the purpose of holding the same in closed position. This method, since it has been adopted and is still being used in the older forms of parasols or umbrellas is proof that it has served its purpose admirably, but with the coming of the new type of parasol or umbrella, having a somewhat shortened handle, it becomes necessary to provide other means for serving this purpose and to this end, I have devised a handle, neat and attractive in appearance and especially adapted for the purpose hereinbefore set forth.

My invention therefore contemplates the embodiment of means for the reception of the rib tips of the umbrella and since said ribs, when in folded position, have a tendency to expand outwardly, this slight pressure is taken advantage of and materially assists in the successful operation of my device.

I further provide my device with reciprocating means which may be retarded sufficiently so that the folding of the ribs may clear said means, and when contiguous to the handle, said means may be automatically advanced and thus the ribs are held in closed position.

Referring now more specifically to the accompanying drawings, let the numeral 5 denote generally my improved handle, which is composite in nature and comprises essentially the body portion 6, having one end recessed and threaded to receive the handle portion 7 of an umbrella or parasol, the other end of said body portion is reduced in diameter to form a shank portion 8, the outer end thereof being threaded into the knob 9, as clearly shown in Fig. 2. Said knob 9 may be apertured as indicated at 10 to receive a loop 11 for the obvious purpose of conveniently transporting the article from place to place. This latter arrangement, of course, is more or less arbitrary, as said knob 9 may be provided with a screw eye to receive practically any attaching means.

The movable portion of my device, denoted by the numeral 12, is provided with an axial bore 13, for the reception of the shank

portion 8, the same being increased in diameter, as indicated at 14, to define a shoulder 15, upon which abuts one end of a coiled spring 16, the latter encircling said shank 5 portion 8, and bearing against the lower face of said knob 9. The bore 13 of said movable part 12 is further increased in diameter, as indicated at 17, into which partly extends the lower portion 9^a of said 10 knob 9.

Upon inspection of Fig. 2, it will be observed that the spring 16 is holding the part 12 against the shoulder 6^a, presented by the reduction of the body portion 6 in the development of said shank portion 8, or in other words, the shoulder 6^a limits the forward movement of the part 12, as is well understood.

Fig. 3 of the drawings shows the tips of 20 the rib R secured by the movable part 12, said tips fitting within the socket 18. It will now be clearly understood that when the ribs are brought down to folded position, the tips thereof will lie adjacent to the outer 25 periphery of the part 12, and it is necessary to retract said part in order to permit the further folding of said tips toward the handle 7 and under such circumstances, it is only necessary to grasp the part 12 and 30 draw same rearwardly, whereupon the tips may lie against the handle 7, and when in this position, said part 12 may be released and under the influence of the spring 16 will assume the position shown in Fig. 3, and 35 thus secure the tips of the ribs from outward displacement. The action here is really two-fold in that the spring 16 is constantly urging the part 12 against the tips of the ribs, whereas the slight resilient action of the ribs 40 themselves cause the same to exert slight pressure against the sides of the socket 18.

When the umbrella or parasol is to be opened, it is only necessary to again retract the part 12, the inherent springy nature of 45 the ribs causing the tips thereof to emerge from the socket 18, whereupon, the movable part may again assume the position shown in Fig. 2 and the umbrella raised as desired.

50 The slight modification depicted in Fig. 4 is very similar to the preferred form exhibited in Figs. 1 to 3, inclusive and has really been designed to disclose a fanciful exterior delineation of the handle proper. Here the 55 body portion 20 is provided with a socket portion 21, the exterior portion thereof sweeping from the base of said body portion 20 to define a very graceful curvature, the exterior portion between the socket and the 60 upper part of the handle has been neatly and attractively formed to appeal to the feminine taste. As in my preferred form, said body portion 20 is transversely apertured, as indicated at 22, for the reception 65 of any desired supporting means either in

the form of a loop or otherwise. The body portion is provided with an axial bore 23 extending a suitable distance therein and as distinguished from my preferred form, said bore is of equal diameter throughout, which, 70 of course, reduces the cost of manufacture in that a single operation provides the bore. The parts mounted within the bore comprise a stem 24, which is of lesser diameter than the bore 23 and carries on its upper end a 75 head portion 25, the latter having a diameter equal to that of the bore. The outer end of said stem 24 is provided with a collar 25^a, which is recessed and threaded as indicated at 26 for the reception of the handle 7 of the umbrella or parasol. A sleeve 27 is fitted within the bore 23, having its outer end extending within the socket 21, while its other end terminates short of the base portion of the bore 23 so that the end thereof forms 80 a shoulder portion against which abuts a spring 28, further engaging the lower surface of the collar 25. The collar 25^a, positioned at the outer end of said stem 24, abuts 85 the end of the sleeve 27, and serves to limit the inward movement of said stem 24, under the influence of the spring 28. Of course, it is quite apparent that the other collar 25 might equally serve as well in that it may engage the end of the bore 23, but I prefer 90 to introduce the collar 25^a, since it really permits me to positively regulate the movement of the stem, as I do not think I can safely rely upon the equal depth of the bore in each instance. The collar 25^a further 95 serves as a brace for the handle when the umbrella or parasol is open and subject to wind pressure.

In the operation of this modified form, when it is desired to close the umbrella, it is 105 only necessary to draw rearwardly on the portion 20 until the tips of the ribs clear the socketted portion 21 and then upon release of the part 20, said tips are snugly nested within the socket 21 and held therein.

110 The illustration in Fig. 1 shows the exterior of my improved handle devoid of any attempt of artistic ornamentation, but of course, it will be understood that colors and designs may be embodied therewith in order 115 to present a tasteful and neat attachment to accompany the design of the main portion of the parasol or umbrella.

I claim:

120 A device of the character described, comprising a body portion adapted to be secured to an umbrella or parasol and having a shank portion reduced in diameter to present a shoulder intermediate the ends of said body portion, a knob carried by the upper end of said shank portion, a reciprocatory member having a socket portion and having an axial bore adapted to receive said shank portion, said bore being increased in diameter to define a shoulder and further in 125 130

creased in diameter to slidably receive the lower reduced portion of said knob and to define a second shoulder and tensioning means positioned within the last-mentioned bore abutting the first-named shoulder and the face of said knob, said tensioning means constantly urging said body portion

against the shoulder in said body portion, and said second shoulder cooperating with the inner face of said knob to limit the outer ¹⁰ sliding movement of said reciprocatory member.

In testimony whereof I affix my signature.
AARON BERKOWITZ.
